UNITED STATES PATENT OFFICE

170,344

PROJECTION APPARATUS

James Y. Taylor, Garland, Tex.

Application August 2, 1951, Serial No. 16,114

Term of patent 14 years

(Cl. D61—1)

To all whom it may concern:

Be it known that I, James Y. Taylor, a citizen of the United States and resident of Garland, in the county of Dallas, and State of Texas, have invented a new, original, and ornamental Design for Projection Apparatus, of which the following is a specification, reference being had to the accompanying drawings, forming part thereof.

Fig. 1 is a perspective view of a projection apparatus, embodying the design;

Fig. 2 is another perspective view thereof; and

Fig. 3 is still another perspective view thereof.

On the drawings, the characteristic features of the design are shown in full lines,

I claim:

The ornamental design for a projection apparatus, substantially as shown and described.

JAMES Y. TAYLOR.
